UNITED STATES PATENT OFFICE.

CHARLES EVAN FOWLER, OF NEW YORK, N. Y., ASSIGNOR TO FOWLER ENGINEERING CORPORATION, OF NEW YORK COUNTY, NEW YORK, A CORPORATION OF NEW YORK.

THEATER STRUCTURE.

Application filed February 23, 1924. Serial No. 694,756.

My invention relates to a theater structure and more particularly to a structure embodying balconies or mezzanines set back in cascade or step form.

5 The present invention is more particularly intended as an improvement on the theater structure forming the subject matter of an application filed by me April 11, 1923, Serial Number 631,426.

10 The general object of the present invention is to provide a theater structure improved in various particulars especially with respect to the cantilever arrangement of the mezzanines relatively to their supporting elements, to the end that supporting posts beneath the several mezzanines are eliminated, a cantilever relation between the mezzanines and oblique supporting beams is established and whereby a greatly improved

15 structure results.

A further object of the invention is to provide cantilever brackets of suitable arrangement entering into the support of the mezzanines and all inter-related through the 20 medium of their supporting means, whereby the cantilevers represented by the mezzanines and brackets are made interdependent and correlated.

The invention also has for an object to 25 provide a structural assemblage in which a triangular formation is embodied formed by oblique truss beams that connect with the mezzanines, and the vertical and horizontal elements at the back of the truss beams.

30 The invention furthermore contemplates an assemblage of strut and steady tie means carrying the thrust to the wall columns and bracing.

35 The nature of my present invention and its distinguishing features and advantages will clearly appear as the description proceeds.

40 Reference is to be had to the accompanying drawings forming a part of this specification, it being understood that the drawings are merely illustrative of examples of the invention.

45 Figure 1 is a sectional plan view of a theater structure embodying my invention;

50 Figure 2 is a vertical section, the mezzanines and a supporting truss beam being shown in side elevation;

Figure 3 is a perspective view of the truss beams, end supporting columns, and the 55 strut and steady tie elements connecting the end columns constituting wall columns and the several truss beams;

Figure 4 is a detail sectional plan view of part of the structural elements represented 60 in Figure 3;

Figure 5 is a perspective view of a portion of the elements shown in Figure 3;

Figure 6 is a view similar to Figure 3 but illustrating a modification in the support- 65 ing means;

Figure 7 is a diagrammatic view in side elevation showing a further modification in which a plurality of triangular structural features are embodied;

Figure 8 is a diagrammatic view in side elevation of a further modification in which the balconies or mezzanines are supported by a front wall and vertical columns with the balconies extending in front of the columns in cantilever form, the columns in turn being supported by the anchor ends of the cantilever beams forming part of the balconies or mezzanines.

70 Referring at first to the form of the invention shown in Figures 1 to 5, the numeral 10 indicates a suitable foundation; 75 11, the front wall of the structure; 12, the roof; 13, the proscenium arch; 14, the orchestra floor; 15, the enclosure for the orchestra; 16, the stage; and 17, the screen of a motion picture theater.

80 In accordance with my invention I provide within the theater a series of oblique truss beams 18 extending in this form of the 85 invention from the foundation 10 upwardly and forwardly toward the plane of the front wall A of the structure.

85 The mezzanines 19 are disposed one above another and set back in cascade or step 90 form. In practice in carrying out my invention, the proscenium arch 13 is given an increased height over what is usual in motion picture theaters, in order that there may be a complete visibility of the screen 17 from 100 the uppermost mezzanine which may thus be disposed at a higher elevation than usual with mezzanines and balconies.

95 In the plan, Figure 1, the uppermost mezzanine 19 shown at the upper right-hand 105 corner of the figure is partly broken away

to show the balcony beneath. The balconies are shown with the central aisle 20 and seats 21 are disposed at each side of the central aisle between the same and the planes of the 5 truss beams 18. Also, in the upper mezzanines are shown stepped aisles or passages 22. It is to be understood that the seating and aisle arrangement does not form part of the present invention.

10 The balconies or mezzanines, it will be observed, extend in front of the beams 18 in cantilever formation. In the forms of the invention shown in Figures 1 and 2, an important feature of the illustrated structures 15 is a cantilever bracket assemblage, there being cantilever brackets 23 disposed beneath the front projecting portion of each balcony or mezzanine and inter-related through the medium of the beams 18 from which said 20 brackets and the mezzanines have rigid support. Extending about the upper ends of the several beams 18 is a strut and steady tie 24 shown best in Figures 3 and 5. The ends of the strut tie 24 connect with wall columns 25 25 to thereby carry the thrust to said columns from the beams 18.

In conjunction with the oblique beams 18, I provide a triangular structural assemblage composed of said beams, vertical supporting columns 26 supporting said beams, and the foundation 10.

The triangular structure feature is further developed in the form shown in Figure 7 in which the columns 126 form with the 35 truss beams 118 and the rear portions of the lowermost mezzanine 119 a triangular structure. In this form of the invention the truss beams 118 have support at their lower ends on columns 27. A further triangular 40 formation is provided at the upper ends of the beams 118 by said beams, the front wall 111, and cross beam 28 at the rear of the adjacent mezzanine 119. In this figure the 45 numeral 323 designates cantilever brackets shown diagrammatically and corresponding with the cantilever brackets 23, 123 and 223.

If the form shown in Figure 8 the front wall 211 supports the anchor ends of the cantilever beams 219 forming part of the 50 structure of the mezzanines designated generally by the numeral 319. Vertical columns 29 support the cantilever beams of the lowermost mezzanine and intermediate columns 30 support the cantilever beams of the mezzanines above. The mezzanines extend forwardly in front of the columns 29 and 30 in cantilever formation.

In the form shown in Fig. 2 stairs rise as at 31 adjacent the front wall between the 60 same and beams 18 and connect the several landings 32 at the backs of the respective mezzanines.

In the form shown in Figure 6 stairs 131 are provided between the landings 132 at 65 the rear of the mezzanine 319. In this form

of the invention (Figure 6) the oblique truss beams 218 rigidly support the respective mezzanines 319 and said mezzanines extend forward of said beams in cantilever form. In this form of the invention also inter-related cantilever brackets 123 are provided corresponding with the brackets 23 and disposed beneath the respective mezzanines supporting the same from rigid supports 318. In Figure 6 the lower ends of the truss beams (318) have support on vertical columns 33 and the lowermost mezzanine 319 is supported by a cantilever bracket 223 while cross beams 34 are employed beneath the rear ends of the mezzanines, said cross beams being rigid with the columns 33 at one end and with higher vertical columns 35 at the opposite ends. The beams 318, columns 35, and cross beams 34 constitute triangular formations as in Figures 2 and 7. The parts in Figure 6 corresponding with similar parts in Figure 2 bear corresponding reference characters. The numeral 112 indicates the roof which in Figure 6 is in stepped form.

It is to be noted that the mezzanines in the different assemblages illustrated in Figures 1, 2, 6 and 7 have cantilever relation to the described oblique truss beams and to the cantilever brackets, and in Figure 8 the mezzanines have a cantilever character in their relation to the vertical supporting columns. In all the forms the cantilever elements, it will be observed, are inter-related with each other through the medium of the supporting means and made inter-dependent.

The result is that I produce a complete cantilever structure through the medium of brackets on the beams beneath the seating structures and this without the employment of supporting columns or posts beneath the respective seating structures either in front of or behind the beams.

The described construction is particularly adaptable for motion picture theaters in that it overcomes the objectionable feature of the ordinary theater structure which positions too many seats close to the screen and makes it possible to overcome the constant interruptions of people passing in and out, which objectionable features make for impaired eyesight of the patrons of the theaters.

It is to be noted that the terms "mezzanines" and "balconies" as employed here are well understood to simply refer to seating structures of different sizes, the smaller seating structures disposed one above the other being generally known as mezzanines and it will be clear therefore that the terms are synonymous generically in merely designating seating structures.

I would state in conclusion that while the illustrated examples constitute practical embodiments of my invention, I do not limit myself strictly to the exact details herein illustrated, since, manifestly, the same can

be considerably varied without departure from the spirit of the invention as defined in the appended claims.

Having thus described my invention, I

claim:

1. In a building structure for theaters, a plurality of seating structures disposed one above another, oblique beams affording support in common to the several seating structures, tie means at the upper ends of the beams connecting up the several beams, and means at the ends of said tie means to take the thrust.
2. In a building structure for theaters, a plurality of seating structures disposed one above another, oblique beams affording sup-

port in common to the several seating structures, tie means at the upper ends of the beams connecting up the several beams, and columns at the ends of said tie means where- 20 by the tie means carry the thrust of the beams to said columns.

3. In a building construction for theaters, a series of seating structures disposed one above another and set back successively from 25 the lowermost one upwardly, oblique beams affording support for said seating structures and coordinating the same in interdependent relation to one another, and columns below the lowermost balcony and affording support 30 for the lower ends of said beams.

CHARLES EVAN FOWLER.
